UNITED STATES PATENT OFFICE.

GEORGE W. RITTENHOUSE, OF SEATTLE, WASHINGTON, ASSIGNOR OF ONE-HALF TO
HOMER P. SMITH, OF SEATTLE, WASHINGTON.

BAG-DISPENSING MACHINE.

Application filed December 31, 1925. Serial No. 78,551.

My invention relates to a bag dispensing machine.

The object of this invention is to provide a machine which may be conveniently used for dispensing paper bags singly from piles of bags. The device is intended for use in stores, fruit stands, and the like places where goods are placed in bags for delivery to customers. The invention is intended to draw a single bag from a stack of bags and to bring said bag outside of an enclosing casing where it may be conveniently engaged by the fingers of the user.

The manner of operation of the device is to provide means for holding stacks of bags in flatwise position with the side thereof towards which the bottom has been folded downward and to engage said bag by the inward edge of the folded bottom.

My invention consists of certain novel constructions and combinations of parts which will be hereinafter described and particularly pointed out in the claims. In the accompanying drawings, I have shown my invention embodied in constructions of a specific form which is now most preferred by me. It is, however, well understood that many of the specific features of construction herein shown may be replaced by other and equivalent constructions without, in any sense, destroying the character of my invention. The drawings are therefore to be understood as merely illustrative of the principles of my invention and the type of mechanism which may be employed therein.

Figure 1 is a top or plan view of the mechanism employed for dispensing bags from a pile. Figures 2 and 3 are longitudinal sections through the casing which contains said mechanism, said section being taken entirely outside of the operating parts. Figure 4 is a section taken substantially on the plane of 4-4 Figure 2. Figure 5 is a side elevation of the bag engaging fingers associated with a broken line, which, in a diagrammatic manner, illustrates the manner of movement given said fingers in engaging and removing a bag.

I prefer to enclose the operating parts of my device within a casing 1, which is made of such size as to snugly hold a stack of bags of the size which it is desired to use. These casings would preferably be varied in size for different sizes of bags and the bag would be expected to snugly fill the case. These

casings or holders may be employed as drawers to slip into suitable holding cabinets; such cabinets, however, have not been illustrated.

Such drawers or casings may be freely open at the top, or could be made closed as desired. Means should, however, be provided for easy insertion of the stack of bags. On the under side, the use of a floor to hold the bag, or the provision of transverse supports, such as the bars 2, is immaterial. It is, however, necessary that, at that end which receives the bottom end of the bag, the support be open at the bottom sufficiently to permit removal of the single bag downwardly. At this end, a transversely extending ledge 76 or other analogous support, as 20, is employed for supporting the extreme outer end edge of the bag bottom. This is illustrated clearly in Figures 2 and 3 wherein the stack of bags is indicated at 21.

The end of the casing at which the bottom ends of the bags are placed is provided with an opening, as 10, extending preferably from the supporting edge 20 downwardly. It is through this opening that the bags are withdrawn. Mounted to be reciprocated lengthwise of the bag in guides, as 30, is a slide 3. The bags are supported at sufficient elevation above the bottom 11 of the casing or holder 1, to accommodate the mechanism by which single bags are engaged and removed. The slide 3 carries two bag engaging fingers. One of these, as the finger 4 may be made a fixed finger, that is one which is carried by the slide 3 and has no movement except that of the slide. As herein illustrated, this finger is made as an integral part of the slide. The particular manner of its construction, however, is immaterial. This finger has its outer end positioned at such a level that it will pass above the folded inner edge of the bag bottom as the bag lies in the stack.

Co-operating with the finger 4 is the movable finger 5. This is pivoted at 50 upon the standard which carries the fixed finger 4. It has a rearward extension which lies over the transversely mounted shaft 51. This shaft is journaled in standards 52 carried by the slide and is designed to be given a limited rocking movement. At 53, being the point of such shaft which is beneath the rearward extension of the finger 5, the shaft 51 is transversely recessed so as to form, in effect, a cam by which the rear end of this

finger may be raised when the shaft is rocked upon its axis. The movable finger 5 is normally held with its outer end towards the finger 4 by the use of a spring, as 54, which 5 operates in conjunction with a pin or rod 55.

The transversely extending shaft 51, extends beyond the edge of the slide 3 and is provided with two radially extending arms 56 and 57.

10 The slide 3 is intended to normally be towards the rear end of the bag holding case or drawer. This result may be secured by the employment of a spring connecting the slide with the rear end of the case. The 15 spring as illustrated, is a compound spring, the spring 6 being a helical spring which is secured to the slide at one end, its other end being secured to the opposite end of a tube 61, within which is secured the second spring 20 60, which is secured to one end of the surrounding tube and to the rear end of the casing. The object of this construction is merely to get the possibility of long range or extension into a small space. Such 25 spring, of whatever type employed, should be such as would normally draw the slide to the rear and hold it in its rearmost position.

30 Mounted close along side of the slide, or in whatever position is most convenient and feasible, is a rod 7. This is the operating rod and is mounted so as to be freely reciprocal, and parallel with the guide 30. This rod has two pins or stop fingers mounted thereon. The finger 70, which is placed immediately back of a pivoted bar or arm 72, carried by the slide, is designed by engaging the said arm 72, to cause the slide to move outwardly when the bar is drawn outwardly. At the point 8 is provided a cam 35 finger or bar designed to engage the outer end of the bar or dog 72 to raise it sufficiently so that it will be freed from the pin 70 carried by the operating bar 7. As the 40 slide has been moved out by the engagement of the pin 70 with the arm 72, the springs 6 and 60 have been stretched. Therefore, when the pin 70 and arm 72 are disengaged, the slide and the fingers carried thereby will be retracted. However, the pin 71, 45 which is placed further to the rear upon the operating bar 7 projects to a greater height than the pin 70 and will then engage the bar 72 to cause the slide to again be moved forwardly.

50 At the first movement of the slide forwardly, or towards the discharge opening 10, the fingers 4 and 5 will be caused to engage the folded inner edge of the bag bottom as is shown at 22. The spring 54 causes the fingers to grip the bag bottom. A positive opening of the fingers at the time they are inserted to engage the bag bottom is secured by the engagement of the arm or pin 57 carried by the shaft 51 with a fixed stop as 58.

This, by the rocking of the shaft, opens the fingers. The fingers, therefore, are caused to engage the folded edge of the bag bottom so that when the slide is released for its backward movement, the bag will be pulled backward sufficiently to free it from the supporting ledge 20. Therefore, when the slide is moved outwardly in its final movement, the bag will be carried along therewith so as to draw its end to or beyond the casing, in accordance with the provision made in the design of the device. At this point, as the slide returns, the arm 56 will engage the stop 59, so as to rock the shaft 51 in the opposite direction, which, however, in a similar manner releases the grip of the fingers upon the bag. 70

75 Provision should be made for the automatic return of the operating bar 7. The most obvious means for doing this is a spring. I have shown a spring 73 as connected by one end with the rod 7, as at 74, and by its other end with one end of the bar or arm 75 carried by the slide. By this expedient, that is, by supporting one end of the spring from the slide, the length of the 80 spring can be made less than would be required if this end of the spring be anchored to the casing. Upon the return of the slide under the influence of the springs 6 and 60, finger 57 carried by the shaft 51 will engage 85 a stop or finger 8, so as to assure the turning of the shaft back to the position in which the spring is free to hold the fingers together.

90 The action of this device is as follows: 100 Bags are supposed to have been put in place with the folded bag bottom downwardly and with this end or back toward the outer end of the holder, as is clearly indicated in Figures 2 and 3. When a bag is desired, the 105 operating arm 7 is engaged and drawn outwardly. The first result of this movement is to draw the slide and its fingers 4 and 5 outwardly until they have engaged with the folded inner edge of the bag bottom, as is 110 clearly shown in Figure 2. At this point, the engagement between the lug or pin 70 carried by the operating bar, and the hinged arm 72 carried by the slide, is freed by the raising of the arm 72 through its engagement with the cam incline 8. In consequence 115 the slide is drawn quickly to the rear by the action of the springs thereon. As a result of this, the bag bottom is pulled rearwardly sufficiently to free it from the supporting ledge or bar 20. The pin 71 then engages 120 with the arm or bar 72 to cause the slide to again move outwardly. This outward movement causes the end of the bag to be drawn outwardly so as to project it somewhat beyond the end of the box or container 1. At 125 this point the grip of the fingers upon the bag has been relieved by engagement of the finger 57 with the stop 58. Therefore, when the operating bar is permitted to be with- 130

drawn and with it the slide 3, it will move rearwardly without taking the bag with it. The bag is thus projected to a point where its end may be conveniently engaged with 5 the fingers.

It is, of course, understood that the detailed construction herein illustrated may be varied by a designer so as to make the parts of a lighter type of construction or by any 10 other change such as would naturally be expected of a competent designer.

While I have herein described my device as placed so that the bags are above the bag engaging and removing devices, it is 15 evident that the same results would be secured if the units of the machine were reversed in position, that is, the bags were beneath and the bag engaging and removing mechanism were above the bags.

20 It would also be possible to operate the mechanism if the pile of bags were placed on edge with the bag engaging mechanism alongside. In these positions it might be necessary to hold the bags to the engaging 25 fingers by a spring or equivalent means. I, therefore, desire it understood that I am claiming the bag engaging and removing mechanism irrespective of the position in which the bags may be placed in relation thereto. Also that I claim the method of 30 dispensing bags which consists in engaging them by the inwardly folded edge of the bag bottom.

What I claim as my invention is:

35 1. In a device for dispensing paper bags having folded bottoms, a bag holding compartment adapted to hold the bags flatwise, the end of said compartment which receives the bottom ends of the bags being open below the bags but provided with means for supporting the extreme edge of their bottom ends, means for gripping the inwardly folded edge of the bag bottom to first free it from said end support, and to then withdraw it from beneath the pile of bags.

40 2. In a device for dispensing paper bags having folded bottoms, a bag holding compartment adapted to hold the bags flatwise and having its bottom open at the bottom ends of the bag and provided with a support for the extreme end edges of the bottom, a slide mounted for reciprocation beneath and lengthwise of the bags, a spring acting to return said slide to the rear when released, gripping fingers carried by the slide and adapted to engage the inwardly folded edge of the bag bottom when moved outwardly and means for moving said slide and the gripping fingers outwardly to engage and grip the bag bottom, backwardly to free the bag from its end support and then outwardly to withdraw the bag from the holding compartment.

45 3. In a device for dispensing paper bags having folded bottoms, a bag gripping de-

vice comprising a slide and a guide therefor, gripping fingers carried by the slide, a shaft and a cam device adapted to operate the fingers by rocking the shaft, operating fingers carried by the shaft, fixed stops engageable by the said fingers, and means for reciprocating the slide.

4. In a device for dispensing paper bags having folded bottoms, means for supporting a stack of bags in flatwise position, a 70 guide way extending lengthwise of and below the bags, a slide movable along and controlled by said guideway, bag gripping fingers carried upon said slide and adapted to engage the folded-over bag bottom, a 75 shaft transversely mounted upon said slide and adapted by rocking to open and close the gripping fingers, fixedly positioned stops and co-operating arms, carried by said shaft adapted for engagement when the 80 slide is reciprocated, and means for engaging and reciprocating said slide.

5. In a device for dispensing paper bags having folded bottoms, a bag holding compartment adapted to hold the bags stacked 90 flatwise, the end of said compartment which receives the bottom ends of the bag being open beneath the bags but provided with a bag supporting ledge at the extreme end edge of the bags, gripping fingers movable 95 lengthwise of and beneath the bag and positioned to grip the inwardly folded edge of the bag bottoms, means for moving said fingers outwardly toward the bottom end of the bag to engage the fold of the bag bottom, means for closing said fingers upon the bag bottom, means for backwardly moving said fingers to free the bag from the supporting ledge and for then moving the fingers and the bag gripped thereby to draw 100 the end of the bag clear of the stack and for then releasing and returning the fingers.

6. In a device for dispensing paper bags having folded bottoms, a bag holding compartment having a support for the end edge 110 of the bag bottom and open adjacent thereto at the under side of the bags, a slide mounted for reciprocation lengthwise of and beneath the bags, a spring for returning said slide, gripping fingers adapted to engage the folded back edge of the bag bottoms, an operating bar mounted to reciprocate alongside of said slide and means for releasably engaging said slide and bar, and means for disengaging said slide after 115 a bag engaging outward movement, and for re-engagement to secure the bag delivering movement.

7. In a device for dispensing paper bags having folded bottoms, a bag compartment 125 adapted to receive the bags flatwise and having its bottom open at the bottom end of the bags and provided with a support for the end edges of the bags, a slide mounted to reciprocate lengthwise of and below the 130

bags, a spring for returning said slide, bag gripping fingers carried by said slide, a shaft mounted transversely of said slide and adapted to control the gripping fingers, an 5 operating bar mounted to reciprocate alongside of the shaft, two side actuating projections carried by the bar and separated lengthwise of the bar, a driving finger pivoted upon the slide to extend transversely

over the bar and to swing toward and from the bar, and a fixedly positioned cam adapted to engage said driving finger to disengage it from the first projection of the operating bar.

Signed at Seattle, Washington, this 24th 15 day of December, 1925.

GEORGE W. RITTENHOUSE.
